COMBINED CAN END AND TEAR STRIP OPENER

John J. Luviano, Rydal, Pa., assignor to Crown Cork & Seal Company, Inc., Philadelphia, Pa., a corporation of New York

Filed Dec. 26, 1967, Ser. No. 9,927

Term of patent 14 years

Int. Cl. D9—99

U.S. Cl. D9—255

Fig. 1

Fig. 2

Fig. 3

FIGURE 1 is a top plan view of a combined can end and tear strip opener, showing my new design;

FIGURE 2 is a side elevational view; and

FIGURE 3 is a bottom plan view.

I claim:

The ornamental design for a combined can end and tear strip opener, as shown.
